Runeer Medal Holder Display . . . Runeer (online) 5 pgs. Posted Mar. 7, 2020. [Retrieved Feb. 7, 2022] https://www.amazon.com/dp/B085ML3G9R/ref=olp-opf-redir?ao=1&th=1&psc=1&f_new=true (Year: 2020).*

Primary Examiner — Marie D. Fast Horse*Assistant Examiner* — Jennifer Sierra Yosinski(74) *Attorney, Agent, or Firm* — Rumit Ranjit Kanakia(57) **CLAIM**

I claim the ornamental design for a medal holder, as shown and described.

DESCRIPTION

FIG. 1 is a perspective view of a medal holder showing my new design;

FIG. 2 is a front view thereof;

FIG. 3 is a back view thereof;

FIG. 4 is a left-side view thereof;

FIG. 5 is a right-side view thereof;

FIG. 6 is a bottom view thereof; and,

FIG. 7 is a top view thereof.

The broken lines in the drawings depict portions of the medal holder that form no part of the claimed design.
